UNITED STATES PATENT OFFICE.

WILLIAM J. HAGMAN AND EDWARD H. WRAY, OF PHILADELPHIA, PENNSYLVANIA.

BORING-MILL.

1,141,871.

Specification of Letters Patent.

Patented June 1, 1915.

Application filed December 3, 1913. Serial No. 804,536.

To all whom it may concern:

Be it known that we, WILLIAM J. HAGMAN and EDWARD H. WRAY, both citizens of the United States, residing in Philadelphia, Pennsylvania, have invented certain Improvements in Boring-Mills, of which the following is a specification.

One object of our invention is to so construct a machine for horizontal boring, 10 drilling or milling, that so far as its operating or control levers, handles, wheels, or the like, are concerned, it will have similar equipments on its opposite longitudinal sides, *i. e.*, all of the controlling members 15 found on one side of the machine are duplicated on the other side, and the machine as a whole is practically bilaterally symmetrical, its parts being so disposed in order that it may be rapidly and conveniently operated by a workman, regardless of whether he has previously been accustomed to operate only machines having their control mechanism on but a single side.

These objects and other advantageous ends 25 we attain as hereinafter set forth, reference being had to the accompanying drawings, in which:—

Figures 1 and 2 are elevations of the opposite sides of a machine constructed according to our invention; and Fig. 3 is a plan, 30 partly in section, of the machine shown in Figs. 1 and 2.

In the above drawings, 1 represents the base frame of the machine on which is fixed 35 a vertically extending main post 2, which, as shown in Fig. 3, is so made that its two opposite sides are similar in shape. Also mounted on the base frame, which is more or less elongated according to the nature of 40 the work to be operated upon, is an outboard post 3 which may be adjustable longitudinally of said frame if desired. Also longitudinally adjustable of the main frame 1, upon that portion thereof between the posts 45 2 and 3, is a carriage 4 having a work-supporting table 5 which is adjustable transversely of the frame. Between this table or carriage and the outboard post 3 we provide a supplementary carriage or table 6, which 50 is likewise adjustable longitudinally of the base frame 1.

The main post 3 is preferably made as a hollow casting, open or slotted through its back and front faces and from its top nearly 55 to its base, for the reception of a saddle 7, which is operative on guideways on the

front face of said post. This saddle with its attached parts is counterbalanced by a weight 9 connected to it by a cable 10, guided by suitably placed pulleys, one of which is indicated at 11 as carried on an arm 12 projecting from the top of the main post 8. The various power driven parts of this machine are actuated from an electric motor 13, whose operation is governed by a controller 14, and it is to be noted that the spindle 15 of said controller extends transversely of the machine, having fixed to its ends two operating handles 16 and 16^a.

It is to be understood that this invention 70 is not concerned with the detailed mechanism whereby power is transmitted from the motor 13 to any of the parts driven thereby, and for this reason such mechanism has to a great extent been omitted from the drawings. It is noted, however, that the tool carrying spindle 17 is mounted in the saddle 7, which is vertically adjustable on the post 8, and said spindle, whose rear end is supported in a supplementary bearing 18 carried by 75 the rear part of the saddle, is longitudinally adjustable in the latter by means of suitable gearing (not shown) actuated by a spindle 19 having operating hand wheels 20 and 20^a at opposite sides of the machine.

For controlling the combinations of gearing whereby the speed of operation of the various driven elements may be governed, we provide a spindle 21, having fixed to its opposite ends, at opposite sides of the machine, two levers 22 and 22^a, and for controlling the feed-back gearing we provide a second transversely extending spindle 23 which at the opposite sides of the machine has fixed to it two operating levers 24 and 24^a.

For controlling the movements of the spindle and the so-called milling movement of the saddle in the post 2, we provide a transversely extending spindle 25 having two controlling levers 26 and 26^a on the 100 opposite sides of the machine.

Similarly the feed or traverse of the table or saddle is controlled by a spindle 27 having levers 28 and 28^a, changes of feed are controlled by a spindle 29 having two controlling levers 30 and 30^a, and the reversal 105 of the table and saddle feed or traverse is controlled by a spindle 31 having two controlling levers 32 and 32^a. Further, the longitudinal adjustment of the table by 110 hand is accomplished through another transversely extending spindle 33 whose ends

project at opposite sides and are suitably squared to receive crank handles 34 and 34^a, and the vertical adjustment of the saddle may be accomplished by hand through a 5 spindle 35 whose ends project at opposite sides of the machine and are suitably squared to receive a crank handle. The cross adjustment of the table 5 may be accomplished through a spindle 36 extending 10 transversely thereof and its ends which project at opposite sides thereof, are also squared to receive an operating handle.

From the above description the fact will be appreciated that our machine is externally of a similar construction on its two 15 opposite sides, and its various controlling or operating spindles each has a handle, lever or wheel on each side of the machine so that it may be run by a workman even 20 though he has been previously accustomed to operating a machine whose controlling means were disposed on but one side only. By our construction any adjustment or control of the machine may be made from either 25 side at will, thus allowing the saving of considerable time, which has hitherto been required for a workman to pass from one side of the machine to the other in order to make the necessary adjustments, etc., under operating conditions.

If it be desired to traverse the table 5 by power, this may be accomplished by throwing into operative engagement the members of a controlling clutch, with the result that 35 through other suitable gearing well known to the art, power is transmitted from the motor 13 to said table, and for controlling the operation of the clutch I provide its operating lever 37, which projects at one 40 side of the machine, with an operating handle 38. Said handle through a rod 39 ex-

tending transversely of the machine is operable from the opposite side by means of a second handle 38^a carried by said rod in a position similar to that of the lever 37. Obviously, means may be provided for traversing the outboard post 3 upon the base or bed 1, and said mechanism may be operated through a spindle whose squared ends 45 41 and 41^a project so as to be respectively 50 accessible on opposite sides of the machine.

We claim:—

The combination of a supporting base frame; a bilaterally symmetrical main post mounted thereon and provided with a central slot extending vertically from front to rear; a bilaterally symmetrical saddle adjustably mounted in the slot of the post and extending in the central vertical plane of the base frame; an arm projecting from the 55 top of the post at an angle to said central plane; a pulley on the arm; a cable passing over the pulley and having one end connected to the saddle; a counter weight on the opposite end of said cable; a motor for 60 driving the machine mounted at the rear thereof with its armature shaft in the central plane; a series of spindles for controlling the operation of the machine and extending transversely of the same; with two 65 controlling handles respectively fixed on the opposite ends of each of said spindles in positions to be operated from opposite sides of the machine.

In testimony whereof, we have signed 75 our names to this specification, in the presence of two subscribing witnesses.

WILLIAM J. HAGMAN.
EDWARD H. WRAY.
